OSCILLATING HYDRAULIC NOZZLE
ASSEMBLY

Eric A. Norman, Seattle, Wash.

Application March 23, 1951, Serial No. 217,167

7 Claims. (Cl. 299—66)

1

My invention relates to nozzles for hydraulic operations; and, more particularly, to an oscillating hydraulic nozzle assembly in which oscillation of the nozzle about both a vertical and a horizontal axis is automatically provided by oscillating mechanism operated by a portion of the water supplied to the nozzle, and in which adjustment of speed of oscillation may be made during operation and adjustment of size of angle of oscillation and direction of angle of oscillation may be made.

My oscillating hydraulic nozzle, also termed a hydraulic monitor, is designed especially for use in hydraulic mining operations, even though it may find use in other fields such as in fire fighting. In placer mining, for gold and some other minerals, the material is not mined by digging but by the erosion action of streams of water under fairly high pressure. The hydraulic nozzle is positioned on a lower level than the top of the bank of material desired to be mined and the water is played on the vertical face of the bank.

The most speedy method of eroding the material is to play the water so as to undercut the material whereby portions of the material will break away by the force of gravity as their support is partially cut away. The water is played at the bottom of the bank, back and forth horizontally, at gradually higher levels. When the top level is reached the water stream is returned to the bottom of the bank more rapidly and the process repeated.

There has not been much development in automatic means to play a stream of water; and, normally, one or two men are employed in directing the nozzle. There has been some work done in hydraulic "giants," wherein extremely high pressures are used, and manual direction is difficult, in the form of deflectors mounted on the tip of the nozzle. These are still not automatic and require the constant attention of a worker in directing the deflector, as is shown in McAulay, U. S. Patent No. 2,086,724.

Part of the success of our industrial system is due to various means utilized to substitute automatic machinery for apparatus requiring the constant direction of workers. It is also important to relieve laborers of the monotonous task of operating the machines. Therefore, I think it important to devise means for the automatic operation of hydraulic nozzles used in operations such as placer mining.

The objects of my invention are: to provide automatic means for directing a hydraulic nozzle

in an oscillating movement about either or both a vertical and a horizontal axis; to provide a reversible expandible-contractible link between members of a hydraulic nozzle assembly to produce relative movement therebetween; to provide means whereby said automatic means is adjustable including means for adjusting the speed of oscillation about either the vertical or horizontal axis during operation; to provide an apparatus of relatively light weight so that it may be easily moved from one location to another and yet so constructed that it remains in balance and will not tip over in spite of its light weight; and to provide a hydraulic nozzle assembly that operates with little attention and a small amount of maintenance, and is of relatively economical construction.

These objects are met in my invention by providing a horizontal supply conduit with an upturned end; an intermediate conduit connected to the upturned end to oscillate about a vertical axis; and a nozzle connected to the upper end of the intermediate conduit to oscillate vertically, the nozzle either being made of metal and having a coupling making a pivotal connection between the nozzle and the conduit, or the nozzle being made of flexible material so that the oscillation vertically is by distortion of the longitudinal axis of the nozzle. In the form of construction wherein the nozzle is rigid, the vertical axis of rotation and the center of the coupling permitting rotation about a horizontal axis are on the same vertical line in all positions of the mechanism, thus providing balance of the hydraulic nozzle assembly whereby the apparatus and its support may be relatively light.

The force for oscillation is provided by expandible-contractible links such as hydraulic pistons and cylinders, the piston rod being connected to a first part and the cylinder being connected to a second part that moves relative the first part. The hydraulic piston assembly is provided with water under pressure by tubes leading from the main water conduits. Each cylinder has an associated valve system, operated by the piston rod, to control the direction of water in the cylinder to produce reciprocating movement. Petcocks on the outlet water tubes provide means for controlling the speed of oscillation.

The detail of this construction and the method whereby the objects are met will best be understood by the following description of a structure embodying the teachings of my invention, when read with reference to the accompanying drawings, in which:

Figure 1 is a perspective view of a form of my oscillating hydraulic nozzle assembly;

Figure 2 is a schematic view of the structure as shown in Figure 1, the solid line indicating the center of the main water passageway, and the approximate center of the two coupling elements being indicated, it being shown that they are on the same vertical line;

Figure 3 is an enlarged elevational view, partly in section and with portions broken away, of the upper piston assembly shown in Figure 1 as viewed from the right foreground;

Figure 4 is an enlarged elevational view, partly in section, of the valve assembly taken on line 4-4 of Figure 3;

Figure 5 is an enlarged view, partly in section, taken on line B-B of Figure 3;

Figure 6 is a schematic view of the flow of water in the piston assembly when the piston is moving downward;

Figure 7 is a schematic view of the flow of water in the piston assembly when the piston is moving upward;

Figure 8 is an elevational fragmentary view, in section and enlarged, taken on line 8-8 of Figure 1;

Figure 9 is an elevational fragmentary view, partly in section, of a portion of the piston assembly, similar to Figure 3 except that the piston is moving upward;

Figure 10 is a perspective view, with portions broken away, of a modified form of my oscillating hydraulic nozzle assembly; and

Figure 11 is a side view, enlarged and partly in section, of a fluid outlet from a principal conduit to a piston assembly.

Conduits and nozzle

Referring to Figure 1, conduit 20 is positioned in a substantially horizontal position and forms a working base. It is supported by brackets 22 and the lower ends of the brackets are set in runners 24. Runners 24 have upturned ends 26 so that the structure may be slid on the ground to change locations or to adjust the position, and may be formed from a small T-beam for sturdiness. If the apparatus is to be used in an operation where it is not to be moved, conduit 20 could be fixedly positioned and it would not have to be in a horizontal position.

A source of water supply, under pressure, is connected to water supply conduit 20, by suitable means, at 28. Conduit 20 reduces in diameter as it extends away from the water inlet at 28. This increases the pressure of the water as it passes through the conduit. Conduit 20 bends upward near its outlet to form a vertical portion 30 which carries an annular flange 32 at its upper end.

Intermediate conduit 34 is positioned above flange 32 in a substantially vertical position. The passageway in intermediate conduit 34 deviates slightly to one side just above its lower end, continues upward, and makes a right angle turn in the opposite direction at its top so that the face of its outlet is in an upright plane. An annular flange 36 is positioned at the lower end.

To permit rotation of the intermediate conduit 34 in respect to conduit 20, there is provided a connecting element.

The connecting element has an annular member 38 having a cross section in the form of a rectangle with a half round groove extending around its periphery, and is attached to annular flange 32 by a plurality of tap bolts 42. A second annular

ring 40 having a rectangular annular groove around its periphery is similarly attached to flange 36 by a second series of tap bolts 42. For sealing annular members 38 and 40 in a superposition there are provided C shaped clamping members 44 which have a half round groove extending around the lower inner surfaces and a plurality of inwardly extending fingers 43 protruding from the upper half of their inner surfaces. These fingers 43 extend into the rectangular groove in ring 40 while roller balls 44 are carried in the half round groove and extend into the opposed half round groove in ring 38 locking the two rings and their attached parts together in a frictionless manner. The C shaped clamping members 44 are held together by means of bolts 47 extending through the outwardly extending ears 45. When bolts 43 are loosened, rotation of intermediate waterway 34 is permitted within members 44 while conduit 20 remains stationary.

The water discharge conduit nozzle 46 is connected to intermediate conduit 34 and has a passageway that makes a right angle turn just beyond the joinder of the nozzle and the conduit, and returns gradually in the opposite direction as it extends forward so that the nozzle tip 48 is substantially centered above the vertical portion 30 of conduit 20 in rear elevation, as shown in Figure 8. The center of the water passageways in the conduits and nozzle are shown schematically in Figure 2.

Nozzle 46 reduces in diameter as it approaches the tip 48 and the intermediate conduit 34 similarly narrows slightly, serving to increase the pressure of the water. Nozzle tip 48 is preferably separable from nozzle 46 so that different size and form of opening may be provided or a device with a plurality of nozzle tips might be positioned in place of tip 48 to provide means for changing tips during operation, such as is shown in Eastwood, U. S. Patent No. 609,578. A flexible element may be fixed to the end of nozzle tip 48 to facilitate the horizontal oscillation of nozzle 46, the end of such a flexible element always lagging the movement of nozzle 46 due to inertia and the reaction due to the water passing through that element acting in the opposite direction of the extension of said flexible element tending to push the nozzle 46 in the direction nozzle 46 is moving.

The upper end of intermediate conduit 34 is of a size permitting positioning inside the connecting end of nozzle 46.

The end of the conduit fits against an internal annular projection 50 of the nozzle and the end of the nozzle fits against an external annular flange 52 of the conduit. Ball bearings 54 are positioned between the nozzle and the intermediate conduit to facilitate movement of one in relation to the other, and annular sealing rings positioned between the two members provide a water tight seal.

It should be noted that various other means might be provided to flexibly couple the conduits and the intermediate conduit and the nozzle. The use of ball bearings in the connecting devices is desirable to provide ease of rotation.

Referring to Figures 1, 2 and 8, the approximate center of the connection between intermediate conduit 34 and nozzle 46 is on the axis of rotation between conduit 20 and intermediate conduit 34. This is important for maintaining the apparatus in balance. The movement of water through these parts has relatively little

tendency to bias the top portion no matter how the nozzle and intermediate conduit are turned.

In some operations it may be desired to employ a hydraulic monitor that sweeps only horizontally or one that sweeps only vertically. The depicted structure could be modified by fixedly joining either conduit 20 and intermediate conduit 34 and not employing the mechanism at 56; or by fixedly joining intermediate conduit 34 and nozzle 46, or combining them in one member, and discarding the mechanism at 58.

Oscillating mechanism

The mechanism for producing rotation of intermediate conduit 34 about a vertical axis is indicated generally at 56 and the mechanism for producing rotation of nozzle 46 about a horizontal axis is indicated generally at 58. As indicated by the arrows at nozzle tip 48 in Figures 1 and 2, the nozzle tip may be moved both horizontally and vertically relative the conduit 20.

The mechanism at 56 includes a piston cylinder 58 pivotally attached at 60 to bracket 62 extending from conduit 20. Piston rod 64 has fitting 65 secured on its outer end. Fitting 65 is pivotally connected to arm 66. The upper end 67 of arm 66 forms a horizontal circular surface having up-standing teeth. Bracket 68 is secured to annular member 41 and flange 36 of intermediate conduit 34. The lower end 69 of bracket 68 forms a horizontal circular surface with teeth secured in engagement with the teeth of end 67 of arm 66 by suitable means such as tap bolt 71.

It can be seen that reciprocating movement of piston rod 64 relative piston cylinder 58 will produce oscillation of intermediate conduit 34. Conduit 34 oscillates within an angle the width of which is determined by controls to be described later. The direction of that angle can be changed by adjusting the toothed engagement of arm 66 and bracket 68. Referring to Figure 1, a clockwise turning of end 71 of bracket 68 relative arm 66, as viewed from above, will result in nozzle 46 oscillating horizontally further to the right.

The mechanism at 56 is supplied with fluid under pressure by the tube 70 leading from conduit 20, tube 70 having control means such as petcock 12 for adjusting the flow of water.

Tube 70 must be somewhat flexible or provided with pivoting means to permit sideways movement of the structure at 56.

The mechanism at 58 is similar. Piston cylinder 74 is pivotally secured to bracket 75 extending from intermediate conduit 34. Piston rod 76 is pivotally connected to arm 78 which makes toothed, adjustable engagement with bracket 80 secured to the inner end of nozzle 46. The mechanism at 58 is supplied with water under pressure by tube 82 having petcock 84 for adjusting the flow of water, tube 82 leading from intermediate conduit 34. Reciprocating movement of piston rod 76 will cause nozzle tip 48 to oscillate vertically. The angle of oscillation may be shifted vertically by adjustment of the toothed engagement of arm 78 and bracket 80.

The structure shown in Figures 3, 4, 5, 6, 7 and 9 corresponds to the mechanism at 58 but is typical of the mechanism at 56 and the piston assembly shown in Figure 10. Piston cylinder 74 is open at the top and closed by suitable means at the bottom. Piston 86 is positioned to slide in said cylinder, having suitable structure to prevent passage of water from one side to the other as by having two plates with a flexible sealing member 88 between. Piston 86 is secured to the end of

piston rod 76 by suitable means such as a cap screw. Valve housing 90 has a cylindrical bore on one side of a size to fit over the open end of piston cylinder 74. Housing 90 has an opening in which piston rod 76 is positioned to slide, there being suitable sealing means at 92 to prevent passage of water.

Valve housing 90 has a cylindrical valve chamber 94 with open ends at one side of piston cylinder 74, the longitudinal axes of the chamber and cylinder being parallel. Cylindrical valve 96 is positioned to slide in chamber 94 and there are sealing rings 97 near the top and bottom of said chamber. Passageway 98 leads from water supply tube 82 to valve chamber 94 and then to the upper end of piston cylinder 74. Valve 96 blocks the passage of water through the valve chamber except when a portion having an annular groove 100 is positioned opposite passageway 98.

When groove 100 is so positioned the water from intermediate conduit 34 is free to pass into the piston cylinder and force the piston 86 downward as shown in Figure 6.

Upper exhaust passageway 102 leads from the upper side of piston 86 to valve chamber 94 and then, at right angles, to exhaust petcock 104. When piston 86 is moving upward, groove 100 is positioned opposite passageway 102 and the water from above piston 86 is free to pass out petcock 104, as shown in Figure 7. Petcock 104 may connect with a receptacle or the water may exhaust upon the ground.

Supply passageway 106 extends from passageway 98, near the connection of water supply tube 82, toward the base of housing 90; and connects with horizontal passageway 107 which passes through valve chamber 94; and, making a right angle turn to the side, connects with tube 108 running to the base of piston cylinder 74. When piston 86 has reached its lowest position, valve 96 has descended until an annular groove 110 is in line with passageway 107 and water is free to flow from tube 82, through passageways 106 and 107 to tube 108 and thence under the piston 86 to move the piston upward as is shown in Figures 7 and 9. Plug 112, threaded into valve housing 90, joins passageway 107 at its juncture with passageway 106. This provides an opening for cleaning passageway 107 and it is noted that water supply tube 82 could join the housing 90 at this point instead of joining passageway 98 or separate supply tubes could be used and passageway 106 eliminated.

Exhaust passageway 114 joins passageway 107 between valve chamber 94 and tube 108; extends upward; turns at right angles to join valve chamber 94; and, making a right angle turn to the side connects with exhaust control means such as petcock 116. Petcock 104 may connect with a receptacle or the water may exhaust upon the ground. As piston 86 moves downward, water underneath passes into tube 108; into passageway 107; cannot pass through the valve chamber 94 at this point because annular groove 110 is now in line with passageway 114; passes upward to passageway 114; past the valve chamber 94 by means of angular groove 110; and reaches exhaust petcock 116, as can be seen from Figures 3, 4 and 6.

Control of the amount of water passing into and out of piston cylinder 74 is obtained by varying the opening of petcocks 104 and 116, and thus the speed of movement of piston rod 76 is controlled resulting in a variable speed of oscillation of the nozzle 46. The speed of both up and down movement of piston rod 76 is varied by

adjustment of petcock 84; the speed of downward movement of piston 86 may be decreased by partially closing petcock 116; and the speed of upward movement of piston 86 may be decreased by partially closing petcock 104.

Valve 96 has an axial passageway in which is slidably positioned control rod 118. Control rod 118 extends below the valve housing 90 and stop 120 is secured near the end of the rod. Compression spring 122 is positioned between stop 120 and the lower end of valve 96. Similarly stop 123 is secured to control rod 118 above valve 96 and compression spring 124 is positioned between stop 123 and the upper end of valve 96. Near the center of valve 96 is a pair of V-shaped annular grooves 126. Ball detent 128 is positioned in the valve housing in the path of said V-shaped grooves 126. Detent 128 is urged by a spring 130, the pressure of which may be varied by movement of plug 132.

As control rod 118 moves downward, stop 123 presses against compression spring 124 and spring 124 bearing on valve 96 tends to force the valve down. At the start of the downward movement of rod 118 detent 128 is engaged in the lower V-shaped groove 126 and valve 96 does not move downward until the force of spring 124 is greater than the force of spring 130 at which point valve 96 moves downward until detent 128 engages in the upper V-shaped groove 126. Similarly on the upward movement of rod 118, valve 96 remains in its lower position until the force of compression spring 122 is greater than the force of spring 130.

Control rod 118 is actuated by a lateral arm 134 fixedly attached to piston rod 76 and slidably mounted on rod 118 between two stops 136 and 138 fixed to control rod 118.

As piston rod 76 must travel from a down position the distance between stops 136 and 138 before the control rod 118 is moved and control rod 118 must move upward some distance before the force of compression spring 122 overcomes the force of spring 130 behind ball detent 128, the water is almost exhausted from the upper side of piston 86 before the exhaust passageway 102 is blocked by the movement upward of valve 96 and annular groove 100 is in position so that water may enter through passageway 98 to the upper side of piston 86 to move it downward. Therefore the piston rod 76 makes almost a maximum stroke and nozzle 46 moves a maximum distance up and down. If it is desired that nozzle 46 move a smaller distance up and down then stops 136 and 138 may be moved closer together and valve 96 will cut off the supply and exhaust of water before the maximum stroke is finished as compression springs 122 and 124 are compressed more quickly. Moving stops 123 and 126 closer to valve 96 would serve the same purpose.

The valve assembly may be characterized by the phrase "a full-stroke valve gear having a lost motion connection with a piston rod," valve 96 changing positions on every stroke of piston rod 76 but the connection between valve 96 and piston rod 76 being of a lost-motion type wherein valve 96 does not change positions until near the end of the stroke of piston rod 76. The valve gear is double acting, changing directions as the piston changes directions.

Other means of valve control could be substituted for the embodiment depicted. Lateral arm 134 could be fixedly attached to control rod 118 and stops 136 and 138 be eliminated, the same action being obtained by wider spacing of

stops 120 and 123 from valve 96. Another modification would be to have valve 96 fixedly positioned on control rod 119, stops 123, 120 eliminated, and compression springs 124, 122 mounted between stops 138 and 136 on either side of lateral arm 134. Other forms of valving means could be substituted, as will be apparent to those skilled in the art such as a rotary valving assembly. It is desirable in any form that control means such as petcocks 104, 106, 84 be provided for control of the speed of the piston during operation.

It can be seen that I have provided an oscillating nozzle assembly that is not only completely automatic but also is adjustable as to the direction of the angle of oscillation, by the relative positioning of arms 78 and 66 and brackets 80 and 68; as to the speed of oscillation, by the use of petcocks 72, 84, 104, 116, etc.; and as to the angle of oscillation, by movement of stops 136, 20 138, 137 and 139.

Even though I have only depicted and described an embodiment of my invention in which the oscillating movement is produced by a hydraulic piston mechanism, it should be noted that other devices could be employed to produce a similar action such as a structure powered by a water wheel. A term to describe the devices contemplated in my invention would be "a reversible-expansible-contracible link" which is descriptive of my hydraulic piston mechanism and other similarly operating mechanisms.

Flexible nozzle

A modified form of construction is shown in Figure 10. Conduit 20 and the mechanism for producing rotation about a vertical axis indicated at 56, including the piston rod 64, arm 66 and bracket 68, are similar to the construction shown in Figure 1. Intermediate conduit 140 is formed with a bend approximately 90 degrees. Nozzle 142 is made of flexible material, preferably rubber, and is fixedly secured to the upper end of conduit 140 by ring 144.

Mechanism is provided for oscillation of nozzle 142 about a horizontal axis similar to the mechanism at 53 in Figure 1. The piston assembly 146 is pivotally connected at 150 to bracket 148 extending from intermediate conduit 140. Piston rod 152 is connected to the outer end of nozzle 142 by a pin in fork 154 extending from clamp 156. Clamp 156 secures the outer end of nozzle 142 and nozzle tip 158, there being means to adjust clamp 156 as by bolt 160. Lever 162 is formed as part of clamp 156 and extends backward to provide means for manual operation of nozzle 142 if that be desired at any time. Nozzle tip 158 has a valve at 164 with a handle 166 for shut-off purposes.

The use of the flexible nozzle 142 involves less expense than the construction shown in Figure 1 and yet provides the same vertical and oscillating movement.

In Figure 11 is shown a fluid outlet assembly for passage of water from intermediate conduit 140 to piston assembly 146. Outlet member 170 is threaded into discharge opening 172. Petcock 174 is positioned in outlet member 170. Filter 176 connects outlet member 170 and tube 178 to trap sediment which might clog valve passageways. Baffle 180 collects water and directs it into discharge opening 172.

I have shown an oscillating hydraulic nozzle assembly that is thoroughly automatic and is capable of varied adjustment including adjustment of speed of oscillation during operation.

This is a highly efficient mechanism, requiring little maintenance and of economical construction. A group of hydraulic nozzles may be easily managed by one worker, where in the past it was necessary to have one or more men in constant operation of each nozzle.

I have described various specific embodiments of my invention but it will occur to those trained in the art that various modifications may be made to the apparatus shown without departing from my invention. What I claim is new and patentable is:

1. An oscillating hydraulic nozzle assembly for directing water supplied under pressure, comprising: a water supply conduit having a main portion in a substantially horizontal position and an upturned vertical portion; an intermediate conduit having a water inlet opening in its lower surface, said water inlet opening of said intermediate conduit being connected to the upper end of said vertical portion of said supply conduit in a manner permitting rotation of said intermediate conduit about a vertical axis; said intermediate conduit having an upper water outlet opening in its side; a nozzle having a water inlet opening near one end in its side, said water inlet opening of said nozzle being connected with said water outlet opening of said intermediate conduit in a manner permitting rotation of the nozzle about a horizontal axis; the connection of said nozzle and said intermediate conduit being directly above the connection between said intermediate conduit and said supply conduit; the water passageway in said supply conduit, intermediate conduit and nozzle becoming smaller as it approaches the free end of said nozzle; hydraulic piston and cylinder means, powered by water passing through said assembly, connected to said supply conduit and said intermediate conduit for producing an oscillating movement of said intermediate conduit about a vertical axis, hydraulic piston and cylinder means, powered by water passing through said assembly, connected to said intermediate conduit and said nozzle for producing an oscillating movement of said nozzle about a horizontal axis; means for adjustably controlling, during operation, the flow of water through said hydraulic piston and cylinder means for determining the speed of oscillation; and the connection between said hydraulic piston and cylinder means and said supply conduit, intermediate conduit, and nozzle being adjustable so that the angle of oscillation of said nozzle vertically and horizontally may be changed in direction vertically up and down and horizontally to one side or the other.

2. Oscillating hydraulic nozzle assembly for directing water supplied under pressure, comprising: a water supply conduit having a vertical outlet portion; an intermediate conduit having a lower water inlet opening, said water inlet opening of said intermediate conduit being connected to said vertical outlet portion of said supply conduit in a manner permitting rotation of said intermediate conduit with relation to said supply conduit about a vertical axis; said intermediate conduit having an upper water outlet opening; a flexible nozzle having a water inlet opening near one end, said water inlet opening of said nozzle being fixedly connected to said upper water outlet of said intermediate conduit; hydraulic piston and cylinder means, powered by water passing through said assembly, con-

nected to said supply conduit and said intermediate conduit for producing an oscillating movement of said intermediate conduit about a vertical axis; and hydraulic piston and cylinder means, powered by water passing through said assembly, connected to said intermediate conduit and said nozzle near its free end for producing an oscillating movement of the free end of said nozzle vertically.

3. An oscillating hydraulic nozzle assembly for directing water supplied under pressure, comprising: a water supply conduit having a vertical outlet portion; an intermediate conduit having a water inlet opening in its lower surface, said water inlet opening of said intermediate conduit being connected to said vertical outlet portion of said supply conduit in a manner permitting rotation of said intermediate conduit with relation to said supply conduit about a vertical axis; said intermediate conduit having an upper water outlet opening; a nozzle having a water inlet opening near one end, said water inlet opening of said nozzle being connected to said upper water outlet of said intermediate conduit, the free end of said nozzle being capable of vertical movement independent of said intermediate conduit; hydraulic piston and cylinder means, powered by water passing through said assembly, connected to said supply conduit and said intermediate conduit for producing an oscillating movement of said intermediate conduit about a vertical axis; and hydraulic piston and cylinder means, powered by water passing through said assembly, connected to said intermediate conduit and said nozzle for producing an oscillating movement of the free end of said nozzle vertically.

4. An oscillating hydraulic nozzle assembly for directing water supplied under pressure, comprising: a water supply conduit having a water outlet opening in its upper surface; an intermediate conduit having a water inlet opening in its lower surface, said water inlet opening of said intermediate conduit being connected to said water outlet opening of said supply conduit in a manner permitting rotation of the intermediate conduit with relation to the supply conduit about a vertical axis; said intermediate conduit having a water outlet opening in its side; a nozzle having a water inlet opening in its side, said water inlet opening of said nozzle being connected with said water outlet opening of said intermediate conduit in a manner permitting rotation of the nozzle with relation to the intermediate conduit about a horizontal axis; the connection of said nozzle and said intermediate conduit being directly above the connection between said intermediate conduit and said supply conduit; hydraulic piston and cylinder means, powered by water passing through said assembly, connected to said supply conduit and said intermediate conduit for producing an oscillating movement of said intermediate conduit about a vertical axis; and hydraulic piston and cylinder means, powered by water passing through said assembly, connected to said intermediate conduit and said nozzle for producing an oscillating movement of said nozzle about a horizontal axis.

5. An hydraulic monitor, comprising: a water supply conduit to lie on a supporting surface and form a working base, a water discharge nozzle flexibly coupled to said conduit and movable with relation thereto about an upright axis, and a reversible expandible-contractible link disposed between said conduit and said nozzle off-center of

the latter for flexing said coupling to cause said nozzle to travel through an arcuate sweeping path over the earth relative said conduit, said link including a cylinder having a reciprocating piston therein, a piston rod connected with said piston and extending through an end of the cylinder, a full-stroke slide valve gear for admitting fluid under pressure to one side and then the other of said piston and for accommodating discharging fluid from said chamber, and an arm carried by said rod and having a lost motion connection with said slide valve gear to carry it to its extreme positions at each of which the direction of travel of the piston is reversed and the direction of travel of the nozzle likewise reverses.

6. The structure according to claim 5 in which there also is a flexible connection between said conduit and said discharge nozzle arranged to permit the nozzle to be raised and lowered in upright paths about a horizontal axis, and a second similar expansible-contractible link associated with the parts of said second flexible connection to produce flexing of said second connection.

7. An hydraulic monitor, comprising: an elongated water supply conduit to lie on a supporting surface and including an upwardly directed portion, an intermediate upright conduit superposed over said upwardly directed portion and coupled thereto in a rotatable water-tight manner that permits rotation of the intermediate conduit about a vertical axis, a discharge conduit communicably associated with said upright con-
